UNITED STATES PATENT OFFICE.

ROBERT H. MILLEN, OF CLAY CENTER, KANSAS.

MAIL-SACK CATCHER.

No. 899,456.

Specification of Letters Patent.

Patented Sept. 22, 1908.

Application filed May 12, 1908. Serial No. 432,331.

To all whom it may concern:

Be it known that I, ROBERT H. MILLEN, a citizen of the United States, residing at Clay Center, in the county of Clay and State of Kansas, have invented new and useful Improvements in Mail-Sack Catchers, of which the following is a specification.

My invention relates to the class of mail receivers or catchers for railway rolling stock, which contemplates the use of a receiving hook or fixture and the object of my invention is the production of a receiving hook or fixture of a superior construction to that now in use.

In the drawings: Figure 1 is a perspective view showing my improved hook applied to a car its operative position being shown in full lines and its inoperative position being suggested by dotted lines. Fig. 2 is a plan 20 of the hook. Fig. 3 is a perspective view of the same.

At 1 is shown the doorway of a mail car having mounted on its frame a suitable socket 2 which may be of any pattern and 25 mounted in any convenient or practicable place, but for the present purpose is shown as mounted on the jamb of the frame of the doorway. This socket receives haft 3 of a bar 4, the enlargement 5 positioning the bar 30 and serving as a bearing to withstand the impact of the body to be received or caught. 6 is a handle by which the bar 4 may be rotated together with the parts thereto attached, the hub 6^a of the handle also serving 35 as a clamp to bind into one rigid bundle, the bar 4 and the near ends of the hook shaped rods 7 and 8. These parts may all be welded together at the joint. The outer or 40 forward ends of the bars or rods 7 and 8 are joined or welded into a point 9 which is turned outward and away from the car and which serves as a gatherer and guide for the mail bag or packet in the receiving operation.

At an intermediate position on the point 45 9 is fastened a spring 10 by means of screws or other fastenings 11, the opposite and free end being enlarged to form a catch or retaining plate 12 having a finger hold 13 formed thereon or attached thereto. On 50 the bar 4 is also mounted by means of a bracket 14 and swiveled loop 15 and pivot 15^a, an L shaped rod the forward portion 16 of which is curved as at 17, the rear portion 18 being straight. The exact shape of the 55 L shaped rod is immaterial, provided it approximates a right angle in general outline.

The rear portion of the rod travels back and forth in the slot 19 formed by the rods 7 and 8, the slot being slightly wider in the middle than toward the ends.

60

In the operation of my device any suitable station 20 provided with a support for the mail bag or packet 21, in this case a post 22, is located by a railway, the rolling stock of which is provided with my catcher. The 65 catcher, being in position shown in full lines in Figs. 1 and 2, in the course of the passage of the train or car receives the mail bag or packet between the finger 17 and the point 9, the bag or packet pushing the L shaped 70 rod about on its pivot, until the rod is in the position shown in dotted lines in Fig. 2 and in solid lines in Fig. 3. In this position the portion 18 is wedged and stopped in the convergence of the slot and the end 17 of the 75 part 16 having pushed aside the head or part 12 of the spring 10, in the course of its movement, slips past the head or plate 12, which returns to its normal position and prevents the part 16 from rebounding or 80 reverse movement until the operator in the process of releasing the mail bag pulls out the plate 12 by means of the finger hold 13.

85

To release the bag the operator may catch one end of the bag with one hand and slip aside the plate 12 with the other. After the release of the bag the device is again set by pushing the L shaped rod to the original position as shown in full lines in Figs. 1 and 2, the part 18 being then jammed slightly in 90 the converging slot end 19, to hold the rod from jarring out of the receiving position.

95

When not in use the device may be dropped or turned down, ordinarily by its own weight to the position shown in dotted lines in Fig. 1, when the handle will project vertically and the hook lie back practically flush with the side of the vehicle. It is apparent therefore that my invention provides for the positive receiving and holding of the bag delivered 100 to it.

95

Having thus described my invention the following is what I claim as new therein and desire to secure by Letters Patent:

1. In a mail bag catcher, a hook-shaped receiving arm, retaining means adapted to be operated by the impact of a body, for preventing the rebounding of said body, and a catch consisting of a spring attached to the outer surface of said arm and means for releasing said catch.

105

2. In a mail bag catcher, a hook-shaped

110

receiving arm, pivoted means adapted to be operated by the impact of the bag, for preventing the rebounding of the bag and a catch, consisting of a spring attached to the outer surface of said arm and means for releasing said catch.

3. In a mail bag catcher, a hook shaped receiving arm, and pivoted retaining means adapted to be operated by the impact of the bag, for preventing the rebounding of the bag and consisting of a pivoted L shaped piece adapted to engage the sides of a converging slot.

4. In a mail bag catcher, a receiving arm, means operated by the impact of a bag for preventing the rebounding of the bag, and a catch, consisting of a spring attached to the outer surface of said arm, for securing said means against reverse movement.

20 5. In a mail bag catcher, a hook-shaped receiving arm, retaining means adapted to

be operated by the impact of a bag, and a catch consisting of a spring attached to the outer surface of said arm, for securing the retaining means.

6. In a mail bag catcher, a hook shaped receiving arm, comprising two spaced members united at their ends and adapted to form a converging slot.

7. A mail bag catcher comprising a handle, 30 a mounted bar, a hook shaped receiving arm, a pivoted L shaped retaining piece adapted to wedge in a converging slot formed in the receiving arm, and a spring catch for securing the retaining piece.

In witness whereof, I have hereunto affixed my signature in the presence of two subscribing witnesses.

ROBERT H. MILLEN.
